UNITED STATES PATENT OFFICE.

JULIUS BOEKEL AND JOHN H. SCHERER, OF PHILADELPHIA, PENNSYLVANIA,
ASSIGNORS TO SAID BOEKEL.

THERMOSTAT.

1,141,605.

Specification of Letters Patent.

Patented June 1, 1915.

Application filed October 20, 1914. Serial No. 837,595.

To all whom it may concern:

Be it known that we, JULIUS BOEKEL and JOHN H. SCHERER, citizens of the United States, residing at Philadelphia, in the county of Philadelphia and State of Pennsylvania, have invented certain new and useful Improvements in Thermostats, of which the following is a specification.

This invention relates to thermostats of the double-acting, compound metal bar type and has for its object to provide an easy means for freely suspending a thermostat of this type in a receptacle, the temperature of which it is to govern, such as an incubator, oven &c, the thermostat being freely inserted or withdrawn at will; said object being accomplished by the construction, combination and arrangement of parts herein-after more particularly set forth and 20 claimed.

In the drawings: Figure 1 represents a front elevation of a device embodying our invention, the block carrying the adjustable contact being in cross-section to show the binding post and electrical connection and the other block being partly in section for the same purpose; Fig. 2, a side elevation of the same; Fig. 3, a cross-sectional view on the line 3—3 of Fig. 2; and Fig. 4, a view 30 of the block carrying the movable contact, partly in side elevation and partly in section, showing the binding post and binding screw and adjacent parts.

Referring now in detail to the drawings, 35 1 designates a bar carrying on each end a depending segmental plate 2 adapted to fit over the upstanding collar, neck, ferrule or equivalent tubular part of a receptacle, the temperature of which the thermostat is to 40 control, see Fig. 1, the collar being indicated in dotted lines. A long vertically depending rod 3 has its upper end riveted through, or otherwise secured to, said bar 1 midway between the ends thereof and carries a 45 squared block 4 on its lower end, the compound arms 5 and 6 being fastened by screws 7 or other suitable means to opposite sides of this block 3 so as to have their upper ends lie on opposite sides of the bar 1 and 50 on a line at right angle to the latter, thus being free to move toward or from each other insuring a very quick and delicate governing action. In the present instance these arms 5 and 6 are so constructed that

they move toward each other as the heat 55 units decrease and away from each other as the heat units increase, but this need not necessarily be so in all cases.

Arm 5 is provided at its upper and free end with an insulating block 19 secured 60 thereto by screws or other suitable means and which carries the fixed contact 8 mounted in a bushing 9 held in said block 19 by screw-threaded engagement or other suitable means. This bushing 9 is provided in 65 its rear part with a longitudinal central bore communicating with a bore through the block 19, thus making a continuous passage for the insertion of the end of circuit wire a, said wire being held in the bore of the bushing 9 by a binding screw 10 threaded downward through said block 19 and the upper wall of the bored portion of bushing 9. The arm 6 carries a similar insulating block 11 similarly secured to its upper and free end 75 and in said block 11 is secured a cylindrical internally and externally screw-threaded bushing 12 provided with an external recess 14 to receive the lower end of a vertical externally screw-threaded binding post 13, 80 which has a lateral bore communicating with a lateral bore through said block 11 for the insertion of the end of circuit wire b. A binding screw 15 having screw-threaded engagement with the interior of 85 said post 13 engages said wire and forces it against the bottom of the bore through the latter, thus securely holding it in position.

An adjustable screw 16 engages the internal screw-threads of bushing 12 and carries contact 17 on its inner end, thus permitting adjustability of the thermostat to varying degrees of heat. A nut 18 turning on said screw 16 between its outer end and the outer end of bushing 12 may be turned 95 or screwed forward on said screw to jam against the end of said bushing 12, thus locking the screw 16 and its contact 17 in any desired position of adjustment.

Of course the contacts 8 and 17 are directly opposite each other in order to make circuit when the two arms 5 and 6 move toward each other; also, the bushing 9, contact 8, contact 17, screw 16 and binding-post 13 are of material of high electrical 10 conductivity, so that the circuit would be from the source of electrical energy, not shown, through positive wire a, through

bushing 9, contact 8, contact 17, screw 16, post 13 and negative wire *b* back to the source of electrical energy.

It is quite obvious that various changes and modifications may be made in the construction, combination and arrangement of the different parts of this invention, of which a preferred form only is illustrated and described, without departing from the spirit thereof, and it is our desire and intention to include all such changes and modifications in the appended claims.

Having thus described our invention, what we claim as new and desire to secure by Letters Patent is:

1. A horizontal bar, vertical segmental plates attached to the respective ends of said bar and adapted to fit over an upstanding collar, a vertical rod attached to, and depending from, said bar, and a squared block secured to the lower end of said rod, in combination with two compound metal arms attached at their lower ends to said block and having their upper and free contact carrying arms directly opposite each other to make and break the electrical circuit as said arms move toward or away from each other.
2. A pair of segmental plates adapted to engage a neck or upstanding collar of a receptacle, in combination with means attached to said plates and suspended within said receptacle, a pair of thermoscopic arms attached to said means, but insulated from each other, and extending up between the said plates and electrical contacts carried by the upper ends of said arms for opening or closing an electrical circuit.
3. A pair of electrical contacts and thermoscopic elements to which they are attached, in combination with means adapted to fit on the neck or upstanding collar of a receptacle and intervening means whereby the said thermoscopic elements are suspended within the same.
4. A rod and means adapted to fit on the

neck of a receptacle for suspending said rod within the latter, in combination with compound metallic arms carried by the lower part of said rod, but extending up out of said receptacle, and electrical contacts carried by the upper parts of said arms for thermostatically closing an electric circuit.

5. Means adapted to fit on a tubular part, in combination with a pair of thermoscopic arms and intervening devices suspended by said means, and electric contacts carried by said arms above said means.

6. Means adapted to fit on a tubular part, in combination with thermoscopic arms suspended therefrom, but extending above said means, electrical contacts carried by the upper ends of said arms and means for adjusting one of said contacts toward or from the other.

7. A pair of segmental plates adapted to fit on the neck of a receptacle, in combination with a bar connecting said plates, a rod suspended from said bar, a pair of thermoscopic arms attached at their lower ends to the lower end of said rod for suspending them within the receptacle but insulated from each other and carrying coöperating electrical contacts above said plates for the purpose set forth.

8. A pair of arms adapted to move toward or from each other at their upper ends according to changes of temperature and provided with electrical contacts at said ends, in combination with means for suspending said arms within a receptacle, said means comprising elements adapted to fit upon an upstanding tubular part of the latter.

In testimony whereof, we have signed our names to this specification in the presence of two subscribing witnesses.

JULIUS BOEKEL.
JOHN H. SCHERER.
